ATTORNEY

WITNESS:

UNITED STATES PATENT OFFICE

ANUND O. AAMODT, OF ALEXANDER, NORTH DAKOTA

GUARD FINGER

Application filed May 16, 1928, Serial No. 278,257. Renewed April 27, 1931.

My present invention has reference to a finger guard for harvesters, mowing machines and the like and my primary object is the provision of a finger guard having a 5 ledger plate over which the cutter bar is reciprocated and which plate is of such construction and arrangement that the same may be easily, quickly and securely attached to the body of the finger guard and likewise 10 easily removed therefrom should the same become broken, or for sharpening and replacement.

A further object is the provision of a ledger plate for the guard fingers of harvesters, mowing machines and the like, which is rust proof and which has its forward edge received in a pocket in the guard finger, its rear and widened edge formed with a bendable tongue to be received against the inclined 15 wall of a pocket or opening provided in the body of the guard finger; its edges, to the rear of the teeth thereon, beveled or inclined to be received in inclined recesses provided in the shoulders of the lateral extensions of 20 the guard finger and whereby the wedging of the bendable tongue into the pocket will impart a longitudinal movement to the ledger plate and to cause the said inclined edges thereof to tightly engage with the walls 25 30 provided by the mentioned pockets.

To the attainment of the foregoing the invention consists in the improvement as hereinafter described and definitely claimed.

In the drawings:

35 Figure 1 is a top plan view of a guard finger provided with my improvement.

Figure 2 is a fragmentary top plan view of the guard finger, the improvement being removed.

40 Figure 3 is a plan view of the improved ledger plate.

Figure 4 is a side elevation of the guard finger with my improved ledger plate in applied position thereon, parts being broken 45 away and parts in section.

Figure 5 is a transverse sectional view on the line 5—5 of Figure 1.

Figure 6 is a perspective view looking toward the rear and widened end of the ledger plate.

Referring now to the drawings, the numeral 1 designates the outer end or body of the guard finger of the usual construction, 2 the rear portion thereof which is attached to the usual stationary support. The outer portion of the body, at the top thereof, is formed with the usual rearwardly inclined guard extension 3, there being a shoulder 4, between the upper face or flat ledge 5 of the body and said extension, and this shoulder is centrally formed with a pocket 6 in a line with the ledge surface 5.

The body in a line with the rear of the ledge surface 5 is formed with the usual lateral extensions 7, the same at a suitable distance from their ends being formed with shoulders so that the inner portions of the said extensions are in the same plane as the ledge surface 5. The confronting faces of these shoulders are cut at inward angles, and the beveled walls 8 thus provided are disposed at inclinations, being directed toward the pointed end of the body 1. The body 1, at a short distance inwardly of the rear of the flat ledge surface 5 has a round opening therethrough which is indicated by the numeral 9. The rear wall, at the upper portion of this opening is beveled, as at 10.

A ledger plate, in accordance with this invention is indicated in the drawings by the numeral 11. The ledger plate has its forward and reduced end formed with a tongue 12 to be received in the pocket 6. The ledger plate has its edges inclined from its forward end to its rear end and these edges are provided with teeth 13. To the rear of the teeth the edges of the ledger plate, at the widened end thereof, are formed with non-toothed downwardly inclined walls 14, and the said ledger plate from its said rear end is formed with two slits that provide therebetween a centrally arranged bendable tongue 15.

When the ledger plate is arranged upon the ledge surface the beveled corners 14 thereof are loosely received between the beveled or inclined walls provided by the recessed shoulders on the lateral extensions 7. A punch is arranged against the tongue 15, and is subjected to a force of impact of a hammer or the like so that the tongue will be bent down-

wardly in the opening 9 and the outer edge thereof will contact with the angle wall 10 provided at the rear of said opening. This it will be noted will impart a bodily longitudinal movement to the ledger plate 11, forcing the beveled corners 14 thereof into tight frictional engagement with the beveled or inclined walls 8 and thereby easily and effectively securing the ledger plate on the guard finger. When the ledger plate is to be removed the punch is arranged in the opening 9, but is passed through the rear or bottom face of the body 1 and is again subjected to an impact of force, so that the tongue will be brought out of frictional contact with the angle wall 10, which permits of the ledger plate being readily slid off of the ledge surface 5 of the guard plate.

Having described the invention, I claim:

20 A guard and a ledger plate, said guard having its ledge surface at the rear thereof formed with lateral extensions whose confronting faces are beveled and provided with an opening therethrough arranged centrally between the confronting faces of the extensions and the rear wall provided by the opening and adjacent to the ledge surface being inclined, the ledger plate having its forward end interengaging with the finger guard, its 25 rear corners provided with reduced beveled portions to be received in the beveled confronting faces of the extensions and its center, at the rear thereof slotted longitudinally at spaced points to provide a bendable finger 30 therebetween and which finger is designed to be bent into the opening and to contact with the rear inclined wall thereof.

In testimony whereof I affix my signature.

ANUND O. AAMODT.
